UNITED STATES PATENT OFFICE.

CHARLES A. SEE, OF CHICAGO, ILLINOIS.

DRESS-SHIELD FASTENER.

SPECIFICATION forming part of Letters Patent No. 681,141, dated August 20, 1901.

Application filed June 8, 1901. Serial No. 63,685. (No model.)

To all whom it may concern:

Be it known that I, CHARLES A. SEE, a citizen of the United States, residing at Chicago, in the county of Cook and State of Illinois, have invented certain new and useful Improvements in Dress - Shield Fasteners, of which the following is a specification.

This invention relates to improvements in fasteners to be used for attaching dress-shields to ladies' waists or other garments, and has for its object to provide a simple and efficient fastener by means of which the shield may be readily attached to the waist or other garment or the lining thereof without inconvenience or discomfort to the wearer and which may be quickly and easily removed.

The invention consists in certain peculiarities of the construction, novel arrangement, and operation of the parts thereof, as will be hereinafter more fully set forth and specifically claimed; and in order to enable others skilled in the art to which my invention pertains to make and use the same I will now proceed to describe it, referring to the accompanying drawings, in which—

Figure 1 is a fragmental perspective view of a portion of the waist and sleeve of a garment with a dress-shield attached thereto by means of a pair of fasteners embodying my invention. Fig. 2 is a greatly-enlarged perspective view of one of the fasteners. Fig. 3 is a plan view thereof, and Fig. 4 is an end view showing a portion of the garment and a part of the dress-shield or two pieces of cloth to be secured together in section.

Similar letters refer to like parts throughout the different views of the drawings.

A represents a portion of a waist or other garment, and B a part of the sleeve thereof to the seam of which is fastened a dress-shield C, of the ordinary construction, by means of a pair of my improved fasteners D, which are shown in Fig. 1 of the drawings in about the position they will occupy when in use. The fastener is made of one piece of wire, preferably aluminium, and is bent so as to form a rectangular portion or head d, which is united by means of a connecting-stem d' to a portion or foot d², which is bent to form three sides of a rectangular figure, as is clearly shown in Figs. 2 and 3 of the drawings. The head d and foot d² lie in parallel planes and are so

held by means of the connecting - stem d', which unites a corner each of said portions. The free end of the wire forming the foot portion d² is pointed, as at e, and is slightly deflected inwardly and toward the head or portion d, as is shown in the drawings. By reference to Figs. 3 and 4 of the drawings it will be seen that the foot or portion d² is somewhat smaller in outlines than the portion d and that the pin or pointed portion e is bent inwardly out of the plane of the portion d², so that when the device is in position there will be no danger of the said point pricking the flesh of the wearer.

It will be observed that the wire forming the fastener is bent to form substantially rectangular corners at each of its bends except at the point of the free end e of the wire forming the portion d² or foot. By this construction the objection of a spirally-formed wire is overcome, for it is well known that such formed fasteners will unscrew themselves or work out of the pieces which they are intended to hold together, while by my construction the head and foot portions of the fastener being united by the stem d', which is bent at right angles to said portions, will lock the fastener in position and prevent its accidental removal.

While I have shown the head and foot portions rectangular in shape and prefer to so make them, yet I may form them of other configurations, but maintain them in parallel planes by means of the connecting-stem d', united at right angles to said portions, without departing from the spirit of my invention.

The operation is as follows: The point e of the foot portion is inserted into a portion of the shield and a part of the garment to which the shield is to be attached, when by turning the fastener by means of the head d the foot portion will be caused to pass through the shield and garment until the stem d' is reached, in which position the head portion d of the fastener will rest on that portion of the shield next to the body of the wearer, while the foot portion will rest outwardly therefrom in such a manner that the point e will not pierce or prick the flesh of the wearer. It is apparent that by forming the head portion rectangular, as shown and above described, a better purchase or hold thereon

may be obtained for turning the fastener than if said portion were made circular.

Having thus fully described my invention, what I claim as new, and desire to secure by Letters Patent, is—

1. A dress-shield fastener comprising a wire bent to form a rectangular head portion and a foot portion forming three sides of a rectangular figure, and having its free end pointed and deflected inwardly and toward the head portion, and a stem uniting the head and foot portions and holding them in parallelism, substantially as described.

2. A dress-shield fastener comprising a wire bent to form a rectangular head portion and a foot portion forming three sides of a rectangular figure, the foot portion being somewhat smaller in outlines than the head portion, and a stem uniting the head and foot portions and holding them in parallelism, substantially as described.
